UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed June 21, 1926. Serial No. 117,389.

This invention relates to single-course car roofs of the all-steel riveted-up type wherein heavy gage roofing sheets extend from side plate to side plate of the car and are riveted thereto and to each other to form a load sustaining structure.

The principal object of the present invention is to produce a roof of light weight and of great strength and rigidity. Other objects are to facilitate the manufacture and assembly of the sheets and to effect greater economy of material. The invention consists principally in forming the sheets with steps of substantially the same width and depth that lead inwardly from the sides of the sheets to the middle thereof and extend transversely of the car over the side plates thereof. The invention also consists in the parts and the arrangements and combinations of parts hereinafter described and claimed.

In the accompanying drawing, which forms part of this specification and wherein like symbols refer to like parts wherever they occur,

Fig. 1 is a plan view of a portion of the car roof embodying my invention;

Fig. 2 is a longitudinal section through the roof at the ridge on the line 2-2 in Fig. 1;

Fig. 3 is an enlarged transverse section through one half of the roof, the section being taken on the line 3-3 in Fig. 1;

Fig. 4 is a cross-section through the eaves portion of the roof at one of the joints on the line 4-4 in Fig. 1; and

Fig. 5 is a perspective view of the eaves end portion of a modified form of roof sheet.

Referring to Fig. 1 of the accompanying drawing, my invention is shown in connection with a car having Z-bar side plates 5 arranged with their webs horizontal and with one flange in and extending upwardly. Metal roof sheets 6 extend from eaves to eaves of the car and are provided at their eaves ends with depending flanges 7 that overlap the upstanding inner flanges of the side plates and are rigidly secured to the outer faces thereof by rivets 8. The roof sheets slope downwardly on opposite sides of the ridge to form a pitch or arcuate roof and have flat side marginal portions that are overlapped and secured together by rivets 9.

Angle-shaped supporting members 10 are located beneath the eaves end portions of the overlapped side marginal roof portions of the sheets, with one flange secured to the inner face of the side plates by the rivets that secure the depending eaves flanges 7 of the sheets thereto. The other flange of the supporting members extends inwardly and is secured to the under side of the lap joints by means of the securing rivets 9 therefor.

Running boards 11 extend longitudinally of the car at the ridge and rest on and are bolted to the lateral top flanges of Z-shaped running board saddles 12 whose lateral base flanges rest on the overlapped side marginal portions of the sheets and are secured thereto by securing rivets 9 therefor.

The roof sheets shown in Figs. 1 to 4 are provided with a series of vertically offset surfaces 13 that extend transversely of the car from end to end of the sheets where they are curved down and merge into the flat surfaces of the depending eaves flanges 7 of said sheets. The offset portions of the sheets are preferably of corresponding width and depth and are offset both vertically and horizontally with relation to each other to form a series of flat steps that lead inwardly from the opposite sides of the sheets to the middle thereof and extend parallel to the sides of the sheets from end to end thereof. The sheets shown in Figs. 1 to 4 have their highest surface located at the side margins of the sheet and their lowest portions at the middle thereof, the low middle portions of the sheets being connected to the higher side marginal portions thereof by a succession of raised surfaces, forming an even series of steps leading inwardly from each side of the sheet to the middle thereof.

In the modified form of sheet 6^a shown in Fig. 5, the highest surface is at the middle of the sheet and the lowest surface is at the margins thereof; and said high middle portion of said sheet is connected to the lower marginal portions thereof by series of successive upwardly offset surfaces 13^a. The offset portions extend longitudinally of the sheet from end to end thereof where they are curved downwardly to meet the depending eaves flanges 7^a thereof.

Among the advantages of the present construction are the cheapness with which the roof sheets may be made, due principally to

the simplicity of their design and its adaptability to the die pressing operation, their great strength for a given amount of the metal and the facility with which they may be applied to the roof. It is noted that the shape of the sheets enables ample width and depth of the sheets to be obtained without making the vertical walls or horizontal surfaces thereof excessively wide; and it also permits the sheets to be nested or stacked for shipment. It is also noted that the forming of the sheets with successive steps that extend from end to end of the sheet and are supported at both ends on the side plates greatly increases the capacity of the sheet for carrying vertical load and also affords said sheets great strength for resisting other stresses to which they are subject in practice.

The invention is not restricted to the precise shapes and arrangements of parts shown in the drawings.

What I claim is:

1. A car roof comprising a series of metal roof sheets connected together along their adjacent margins, each of said sheets comprising a series of steps extending from end portion to end portion thereof.
2. A car roof comprising a series of metal roof sheets extending from side plate to side plate of the car and connected together along their side margins, each of said sheets comprising a succession of steps extending transversely of the car from side plate to side plate.
3. A car roof comprising a series of metal roof sheets extending from side plate to side plate of the car and connected together along their adjacent side margins, each of said sheets comprising a succession of steps extending transversely of the car from side plate to side plate, each of said steps having downwardly curved end portions that merge into depending flanges at the eaves ends of the sheets.
4. A car roof comprising a series of metal roof sheets extending from side plate to side plate of the car and connected together and to the car frame, each of said sheets comprising a vertically offset middle portion and a series of steps leading from the adjacent margins of said sheets to the vertically offset middle portions thereof, said steps extending transversely of the car from end portion to end portion of the sheets.

5. A car roof comprising a series of metal roof sheets extending from side plate to side plate of the car and connected together and to the car frame, each of said sheets comprising a vertically offset middle portion and a series of steps leading from the adjacent margins of said sheets to the vertically offset middle portions thereof, said steps extending transversely of the car from near one end to near the other end of the sheets where they are curved downwardly and merge into depending flanges at the eaves ends of said sheets.

6. A car roof sheet comprising a depressed middle portion and a series of steps leading from two opposite sides of the sheet to the depressed middle portion thereof, said steps extending from near one end to near the other end of the sheet.

7. A car roof sheet comprising a depressed middle portion and a series of steps leading from two opposite sides of the sheet to the depressed middle portion thereof, said steps extending from near one end to near the other end of the sheet where they are curved downwardly and merge into depending flanges at the ends of the sheet.

8. A car roof sheet comprising a series of steps of substantially equal length extending lengthwise of said sheet from near one end to near the other end thereof with their ends merging into depending flanges.

9. A car roof sheet comprising a series of steps extending lengthwise of said sheet from near one end to near the other end thereof where they are curved downwardly and merge into depending flanges at the ends of said sheet.

10. A car roof sheet comprising a depressed middle portion and a series of steps extending from opposite margins of said sheet to the depressed middle portion thereof, said steps extending from near one end to near the other end of the sheets.

11. A car roof sheet comprising a depressed middle portion and a series of steps extending from opposite margins of said sheet to the depressed middle portion thereof, said steps extending from near one end to near the other end of the sheets where they are curved downwardly and merge into depending flanges at the ends thereof.

Signed at New Kensington, Pennsylvania,
this 16th day of June, 1926.

CHARLES DAVID BONSALL
